[57] **ABSTRACT**

An inflatable balloon is sealed gas-tight by an apertured disc which pinches together a doubled-over section of the neck of the balloon. A string optionally may be attached to the neck by the same disc.

BALLOON AND SEALING MEANS THEREFOR

This is a division, of application Ser. No. 133,143, filed Apr. 12, 1971, and now U.S. Pat. No. 3,720,991.

BACKGROUND OF THE INVENTION

This invention relates to a balloon, such as an inflated toy balloon, and to a seal for preventing the escape of gas from the balloon.

SUMMARY OF THE INVENTION

One of the objects of the present invention is to provide a new and improved balloon with a comparatively inexpensive and extremely gas-tight seal which may be applied to the balloon in a fast and simple manner without need of either tying cord to or permanently knotting the neck of the balloon.

A further object is to provide a balloon with a tight and secure seal which may be released quickly and easily to enable selective deflation of the balloon.

Another object is to provide a balloon with a unique seal consisting of an apertured sealing disc which not only is effective to pinch and seal the neck of the balloon but which also may optionally serve to anchor a string to the neck.

These and other objects and advantages of the invention will become more apparent from the following detailed description when taken in conjunction with the accompanying drawings.

BRIEF DESCRIPTION OF THE DRAWINGS

FIG. 1 is a fragmentary perspective view of a balloon embodying the novel features of the present invention.

FIG. 2 is an enlarged fragmentary cross-section taken substantially along the line 2-2 of FIG. 1.

FIG. 3 is a front elevation of the sealing disc.

FIG. 4 is a perspective view of a machine for sealing the balloons.

DETAILED DESCRIPTION OF THE PREFERRED EMBODIMENT

The present invention contemplates the provision of a novel balloon 15 having a body 16 and a neck 17 and having a comparatively inexpensive apertured sealing disc 19 which may be attached quickly and easily to the neck to pinch the latter tightly and securely and thereby prevent the escape of gas from the body. In spite of the tight seal thus effected, the sealing disc may be released from the neck easily if there is need to deflate the balloon and, in addition, the disc may be used to anchor a string 20 to the neck if it is desired to provide the balloon with such a string.

More specifically, the sealing disc 19 illustrated herein is made of flexible but self-sustaining plastic, is substantially flat and circular, and is formed with a centrally located hole 21. While the dimensions of the disc may vary, the present disc has an overall diameter of approximately three-fourths inch and a hole with a diameter of about one-eighth inch and is used in conjunction with a balloon 15 whose neck 17 has an expanded diameter of about five-eighths inch.

Sealing of a newly inflated balloon 15 by the disc 19 is effected by first stretching the neck 17 across one face of the disc and then, while holding the body 16 and the outer end of the neck, by forcing an intermediate portion of the neck through the hole 21 sufficiently far to double the neck over upon itself (see FIG. 2). As an incident to being forced through the hole, the doubled-

over sections of the neck are contracted and pinched together by the edges of the hole and are held tightly by such edges to effect a good gas-tight seal preventing the escape of gas from the balloon. The resilient fold of

the doubled-over sections of the neck expands considerably after passing through the hole and forms a knob 23 (FIG. 2) which is much larger than the hole and which retains the disc securely on the neck to prevent the disc from being dislodged accidentally. If it is desired to deflate the balloon, however, the disc may be released by firmly pulling on the inner and outer ends of the neck to force the doubled-over section reversely through the hole. The ease of deflation afforded by the disc is advantageous in that a retail merchandising outlet may deflate any helium-filled balloons remaining unsold in the evening and may re-inflate the balloons for sale at a later time rather than bursting and discarding the unsold balloons.

When a string 20 is to be attached to the balloon 15, the string first is simply interwrapped with the neck 17 prior to stretching the neck across the disc 19 (see FIG. 4). The neck and the string may be interwrapped either by spirally winding a short length of the string around the neck or by twisting the neck around the string. Thereafter, the short length of string is forced through the hole 21 in the disc simultaneously with the neck and thus is doubled over upon itself and is gripped by the contracted, doubled-over sections of the neck as shown in FIG. 2. The string thus becomes anchored securely to the neck at the same time the neck is sealed and without need of tying the string.

Illustrated in FIG. 4 is a machine 25 for automatically attaching sealing discs 19 to a series of balloons 15 in a quick and easy manner.

In general, the preferred machine 25 includes a sealing station 26 (FIG. 4) to which successive discs 19 are delivered automatically. Each time a balloon 15 is to be sealed, its neck 17 (either with or without an interwrapped string 20) is stretched manually across the disc in the sealing station and then is engaged by a power driven needle 27 which first forces the neck through the hole 21 in the disc and then releases the doubled-over neck to enable removal of the balloon 45 and the disc from the sealing station prior to delivery of a succeeding disc to the station. The entire sealing operation may be completed in approximately one second and effects secure attachment of the disc and the string to the balloon.

The machine is described in its entirety in the aforementioned application to which reference may be made for a more complete explanation of the construction and operation of the machine.

From the foregoing, it will be apparent that the present invention brings to the art a balloon 15 with a unique, inexpensive and comparatively gas-tight seal. The seal may be easily applied, easily removed and also may serve to anchor a string to the balloon.

We claim as our invention:

1. A balloon inflated with gas and having a body and a neck, and means for sealing said neck to retain said gas in said body, said means comprising a disc having a hole therethrough, said neck extending through said hole, being doubled over upon and against itself and then extending reversely through the same hole with a portion of said doubled-over portion of the neck intermediate the ends thereof being pinched together by the

edges of said hole to prevent gas from escaping from the open end of said neck.

2. A balloon as defined in claim 1 further including an elongated string having an end portion extending along a portion of said neck, the end portion of said string also being doubled over upon itself, projecting through said hole, and anchored to said neck by virtue

of the edges of said hole pinching said neck against said string.

3. A balloon as defined in claim 1 in which said hole is circular and is formed with a continuous and unbroken edge.
